UNITED STATES PATENT OFFICE.

JOHN W. PAUL, OF KITTANNING, PENNSYLVANIA, ASSIGNOR TO UNION TYPEWRITER COMPANY, OF ILION, NEW YORK, A CORPORATION OF NEW YORK.

TYPE-WRITER.

971,469.

Specification of Letters Patent. Patented Sept. 27, 1910.

Application filed August 13, 1906, Serial No. 330,330. Renewed January 7, 1909. Serial No. 471,162.

To all whom it may concern:

Be it known that I, JOHN W. PAUL, a citizen of the United States, residing at Kittanning, in the county of Armstrong and State of Pennsylvania, have invented new and useful Improvements in Type-writers, of which the following is a specification.

This invention relates to typewriters and consists in certain improvements in the construction thereof as will be hereinafter fully described and pointed out in the claims.

Figure 1 shows a section on the line 1—1, 1—1^a, 1^a—1^b in Fig. 2. Fig. 2 a section on the line 2—2 in Fig. 1. Fig. 3, a section on the line 3—3 in Fig. 1. Fig. 4, a side elevation of a segment of the auxiliary frame showing the stops for the basket. Fig. 5, a section through the same mechanism. Fig. 6, a side elevation, with parts removed to better show the construction, of the shift mechanism.

A marks the main frame of the machine which may be of any desired construction. The platen B is mounted on this frame and is provided with the ordinary ribbon spools C and type bar guides D.

The machine shown is of the front strike type, but is not in all respects limited to this type of machine.

Arranged within the main frame is an auxiliary frame E. The auxiliary frame is formed of sheet metal. The sheet metal sides e, e' have the rear ends e^a and front ends e^b. The sides are provided with the notches e^a and e^b which engage the pins a and a', extending inwardly from the main frame. The notch e^b is cut away at e^b to permit of the insertion of the auxiliary frame. In a general way this construction is shown in a patent granted to me on October 7th, 1908, #901,998.

The type-basket F has the segment f arranged in a vertical plane in such position relatively to the platen as to form the printing point thereon in front of the platen. The basket has the supporting legs F' to which are pivotally connected the parallel bars H, H, by means of screws h' h'. There are two of these bars H, one above the other, at each side of the basket, thus forming two sets of parallel bars. The front ends of these bars are rigidly secured to the rods h h extending across the front of the auxiliary frame. Thus the upper and lower bars at one side are rigidly connected with the

upper and lower bars respectively at the opposite side of the basket, and in consequence their paralleling action is rendered more efficient. These bars guide the segment as it is shifted to a position to produce a lower or upper case impression and maintain the segment in substantially the same plane or at least in planes parallel in the different positions. Where the basket is pivoted on a single pin and shifted, it shifts the angular relation of the segment relatively to the platen and it is difficult to maintain the alinement of the different type-bars, the change of angle having a different effect on the end type-bars than upon those near the center of the basket. With this shift this is obviated in that the segment maintains the same angular relation relatively to the platen and at the same time the desirable feature of a pivotal mounting is retained.

The type-bars G are mounted on the segment F and normally lie toward the front of the machine, and are pivoted on a rod g which extends through all the type bars. They are provided with the type g', each bar having an upper and lower case letter. The rods I are pivotally connected with the heels g^a of the type-bars and extend forwardly from these through a guide plate I'. The rods I are free to move through this guide plate, this plate forming a guide for the rods. The perforations through the guide plate are arranged in an arc corresponding to the segment for the type-bars, the segment being arranged so that the different rods I have approximately the same relation to the type bars to which they are attached. Push rods J are arranged beneath the rods I and approximately parallel to the bars H—H. They have the forked ends j and j^a. The end j is pivotally connected with the bracket i' on the rod I and the forked end j^a is pivotally connected to the rock lever K thus forming a link between the lever K and rod I. The rod J is provided with the right and left screw threads j^b j^c which are secured to the ends j and j^a and locked in position by the jam nut j^d j^e. By this means the length of the rod may be adjusted so as to give the proper length to each connection. The rock lever K has the forwardly extending arm k, the whole forming an angle lever. A slot k' is arranged in the arm k. The levers are pivot-

ally mounted on a rod K extending across the auxiliary frame.

The key levers L are provided with the notches l which engage the rear plate e² of the auxiliary frame. A spring l' extends through a perforation e¹⁰ in rear plate e². It has the downwardly extending portion l² and horizontal portion l³. The horizontal portion extends through a perforation l⁴ in the key lever. This spring exerts the usual spring tension on the key lever. The key lever is provided with the usual finger piece l⁵ and the pin l⁶ extends from the side of the key-lever through the slot k' for communicating the movement of the key-lever to the rock-arm K. It will readily be seen that upon the depression of the key-lever, the rock-lever K is swung toward the front of the machine and this, acting as a lever of the first order upon the push rod J, actuates the rod I and consequently the type-bar connected with the type-bar action. The rock-levers K are preferably of different lengths so that the top ends of the levers each present about the same relation to the rods I. The pins l⁶ are located on the different key-levers in such relation to the levers K as to give to each key-lever the same depression to effect the excursion of the type-bar to the printing point.

It will be noted that as the basket is shifted for upper or lower case letters, the rods I are moved with the basket. The rear ends of the parallel rods H in lower case position are slightly below the rods h—h so that as the basket is swung upwardly it moves slightly toward the rear of the machine. The upper ends of the rods J, it will be noted, also swing in this direction, their initial position being somewhat nearer the horizontal than the rods H. The total swing leaves the key-levers in their normal position, that is, the front ends of the rods J swing toward the rear of the machine sufficiently to compensate for the rearward swinging of the type-basket or vice versa.

It is desirable to get a quick initial return movement to the type-bar action. To effect this result, I provide the bar M which is arranged in the path of the rock levers K. The bar M is mounted on the levers M', these levers being pivoted at m on the auxiliary frame. A spring m' is secured to the lever M'. The bar M engages the rock-levers just prior to the end of their stroke and gives to them a quick, snappy initial return movement. This bar is picked up by the rock-levers later than is feasible with the ordinary spacer bar, and being independently mounted is free from the frictional disturbances of the universal bar. In Fig. 2 I show the usual spacer bar N.

In order to provide convenient stops for the shift, I strike out from the sides e—e' of the auxiliary frame the ears e' e'. The

screws e⁸ e⁹ are arranged in these ears and lock nuts e⁹ e⁹ are placed on the screws. These screws operate on the pin f' extending from the basket.

In a patent issued to me June 26, 1906, Serial No. 824,579, I have shown a reverse shift mechanism. In this application I show an improvement on the shift mechanism shown in my patent. An auxiliary shift lever O is pivotally mounted on the screw o secured in the side plate e'. This shift lever is provided with the slot o' extending each side of the pivotal support o. A pin o² operates in this slot. The pin is carried by a link o³. The link o³ is pivotally connected with the shift lever O'. The auxiliary shift lever O has a slot o⁴ in its rear end which engages a pin f' on the basket. An arm o⁵ extends upwardly from the auxiliary lever O and a spring O³ connects the upper end of this arm with a reversing lever O². The reversing lever O² is pivoted on the screw o and has the Y shaped end o⁶ with the arms o¹⁰. An operating lever O⁴ is pivoted at o⁶ on the frame. This is provided with a slot o⁷ which engages a pin o⁸ on the reversing lever O². With the parts in the position shown in Fig. 6, it will be noted that a depression of the shift lever O' acting through the link o³ on the auxiliary shift lever O will depress the front end of this shift lever and acting on the screw O as a fulcrum, lift the type-basket. When, however, the operating lever O⁴ is lifted, the lower end of the reversing lever is moved toward the right and the arm o¹⁰ of the fork engages the pin o² and carries it to the opposite side of a pivot o. At the same time it carries the pin o⁸ which is an anchor for the spring o³ to the opposite side of the pivot so that it tends to swing the auxiliary lever O upwardly and the spring is of such strength as to effect this result and therefore normally hold the basket in the upper position. A depression, then, of the shift lever operating through the link o³ and the upper end of the lever O will depress the basket and upon the release of the shift lever the basket will be returned to the upper position through the action of the spring O³. I prefer to approximately balance the weight of the basket by means of the spring h² which extends from the plate I' to the lower bars H. One of these springs is arranged at each side of the basket.

What I claim as new is:

1. In a typewriter, the combination of a frame, a platen having a printing point thereon facing the front of the machine; a type basket comprising a type bar segment; type bars normally lying toward the front of the machine and in a horizontal position; a mounting for said basket comprising parallel bars pivotally secured to the rear of the basket and extending forwardly in the same general direction as the type bars and hav-

- ing their front ends pivotally secured to the frame whereby the type bars and parallel bars may all be assembled in and occupy the same general part of the machine.
- 5 2. In a typewriter, the combination of a frame; a platen mounted in the frame; a type basket; type bars in the basket and normally extending toward the front of the machine; parallel bars having their rear ends pivotally secured to the rear of the basket and extending forwardly; rods $h-h$ pivotally mounted on the frame to which the parallel bars are secured, said rods being in front of the type bars.
- 10 3. In a front strike typewriter, the combination of a platen; a type-basket containing a system of type-bars; a mounting for said basket comprising parallel bars, said mounting being arranged to compel a slight rearward movement of the basket during the case-shift and to maintain all the parts of the basket in a position parallel to the same parts in the normal position of the basket; a key-lever mounted independently of the type-basket; and a connection between the key-lever and its associated type-bar, arranged to compensate for the rearward movement of the parts as the type-basket is shifted in its mounting.
- 15 4. In a type-writer the combination of a type-bar; a finger piece; a connection between the finger piece and type-bar for communicating the movement of the finger piece to the type-bar comprising a key-lever, a rock-lever actuated by the key-lever, a push rod extending from the rock lever toward the front of the machine and a rod extending from the type-bar toward the front of the machine with which the push rod is connected.
- 20 5. In a type-writer the combination of a type-bar; a finger piece; and a connection between the finger piece and the type-bar including a push rod arranged to actuate the type bar on the movement of the rod toward the front of the machine, said push rod being arranged beneath the type-bars and the front of said rod being in front of said rear end of the type-bar, and a rod extending from the type-bar toward the front of the machine connected with the push rod.
- 25 6. In a type-writer the combination of a type-bar; a shifting mounting for said type-bar; a finger-piece; and a connection for communicating the movement of the finger-piece to the type-bar, including a rod extending from the rear of the type-bar toward the front of the machine, a push rod connected therewith and adapted to actuate said rod by a movement toward the front of the machine, said push rod being pivotally mounted and of such length and so disposed relatively to the shifting mounting for the type-bar as to compensate therefor as the type-bar is shifted.
- 30 7. In a type-writer the combination of a type-bar; the sliding rod I extending from the type-bar to the front of the machine having a pivotal connection with the type-bar; a mounting in which the rod I is slidingly mounted toward the front of the machine; the push rod J pivotally secured to the rod I; and means for actuating the push rod.
- 35 8. In a type-writer the combination of a type-bar; the sliding rod I extending from the type-bar toward the front of the machine and having a pivotal connection with the type-bar; a guide in which the rod I moves toward the front of the machine; the push rod J pivotally secured to the rod I; means for actuating the push rod; a shifting mounting for the type-bar; said mounting and push rod swinging in opposite directions, the movement of one compensating for the movement of the other as the type-bar is shifted.
- 40 9. In a type-writer the combination of a type-bar; a sliding rod I extending from the type-bar toward the front of the machine and having a pivotal connection with the type-bar; a guide in which the rod I moves toward the front of the machine; the push rod J pivotally secured to the rod I; means for actuating the push rod; and means for adjusting the length of the push rod.
- 45 10. In a type-writer the combination of a type-bar basket; a pivotal mounting for said basket comprising parallel rods; a type-bar mounted in said basket; the rods I pivotally connected with the type-bars; a guide in which said bars slide; and push rods J connected with the sliding rods and being disposed to swing as the basket is shifted to compensate for the swinging movement of the basket.
- 50 11. In a type-writer the combination of a type-bar; a push-rod arranged beneath the type-bar and adapted to actuate the type-bar by a forward movement thereof; a rocking lever for actuating the rod arranged beneath the push rod having a slotted arm; means acting on the slotted arm for actuating the rock lever; and means for adjusting the length of the push rod.
- 55 12. In a type-writer the combination of a type-bar basket comprising a vertical segment; a series of type-bars mounted on said segment; the sliding rods I for actuating said type-bars; a slide mounting for said rods I, said mounting being arranged to give to the rods a curve approximating the curve of the segment; a series of push rods arranged under the sliding rods; and a series of rock levers connected with said push rods, said rock levers being pivoted on a common axis and being of different lengths

to give the top of said rock levers approximately the curve of the type-bar segment.

13. In a type-writer the combination of a type-bar basket comprising a vertical segment; a series of type-bars mounted on said segment; the sliding rods I for actuating said type-bars; a slide mounting for said rods I, said mounting being arranged to give to the rods a curve approximating the 10 curve of the segment; a series of push rods arranged under the sliding rods; a series of rock levers connected with said push rods, said rock levers being pivoted on a common axis and being of different lengths to give 15 the top of said rock levers approximately the curve of the type-bar segments; and a shifting mounting for the basket arranged with relation to the push rods to make the swinging of the push rods compensate for 20 the shifting movement.

14. In a type-writer the combination of a type-bar basket comprising a vertical segment; a series of type-bars mounted on said segment; the sliding rods I for actuating 25 said type-bars; a slide mounting for said rods I, said mounting being arranged to give to the rods a curve approximating the curve of the segments; a series of push rods arranged under the sliding rods; a series 30 of rock levers connected with said push rods, said rock levers being pivoted on a common axis and being of different lengths to give the top of said rock levers approximately 35 the curve of the type-bar segment; and a mounting in said basket comprising parallel rods, the parallel rods being arranged relatively to the push rods to swing in a direction to compensate for the swinging of the push rods as the basket is shifted.

15. In a type-writer the combination of a platen; a type-writer and devices for shifting the relation between the basket and platen comprising a shift lever; the pivotally mounted auxiliary shift lever O; the link 40 o⁴ secured to the shift lever and having a connection with the auxiliary shift lever permitting a movement to either side of the pivot of the auxiliary shift lever; a reversing lever for shifting the link; a spring 45 tensioned between the reversing lever and auxiliary shift lever, the reversing lever forming an anchor for the spring and shifting to the opposite side of the pivot of the auxiliary shift lever as the auxiliary lever is 50 operated.

16. In a type-writer the combination of a platen having a printing surface thereon; a type-basket and devices for shifting the relation between the basket and platen comprising a shift lever, the change of relation 60 between the basket and platen being in a direction parallel to the printing surface; the pivotally mounted auxiliary shift lever O; the link o⁴ secured to the shift lever and 65 having a connection with the auxiliary shift

lever permitting a movement to either side of the pivot of the auxiliary shift lever; a reversing lever for shifting the link; a spring tensioned between the reversing lever and auxiliary shift lever, the reversing lever forming an anchor for the spring and shifting to the opposite side of the pivot of the auxiliary shift lever as the auxiliary lever is operated; and an operating lever for operating the reversing lever.

17. In a type-writer the combination of a platen; a type-basket and devices for shifting the relation between the basket and platen comprising a shift lever O'; the auxiliary shift lever O having the slot o'; the link o⁴ pivotally connected with the lever O' and secured to the pin o²; the pin o² extending through the slot o'; the pivotal support o in the auxiliary shift lever; the reversing lever O², pivotally mounted on the support o, one end being arranged to engage the pin o²; the arm o⁵ extending from the auxiliary lever O; the spring O⁵ extending from the arm o⁵ to the lever O²; and the operating lever O⁴ for actuating the reversing lever O².

18. In a type-writer the combination of a main frame; an auxiliary frame mounted in the main frame, said auxiliary frame being formed of sheet metal and having the ears e⁷ e⁸ struck up from the same carrying the stops for the type-basket; and a shifting type-basket carried by the auxiliary frame.

19. In a typewriting machine, the combination of a substantially vertically disposed segment, a platen arranged above the segment, a series of segmentally arranged upwardly and rearwardly striking type bars which are adapted to strike against the front face of the platen and which normally extend substantially horizontally toward the front of the machine, parallel shift arms which are arranged at different elevations and extend fore and aft of the machine and on which said segment is carried and by which it is guided in its up and down case shifting movements, said arms turning on fixed centers forward of the type bar segment type bar actuating links which are operatively connected to the type bars and extend beneath the type bars fore and aft of the machine and which normally are substantially parallel with said parallel shift arms, angle levers pivoted to a relatively fixed portion of the machine and connected with said links, and key levers carried by a relatively fixed portion of the machine and operatively connected to said angle levers.

20. In a typewriting machine, the combination of a substantially vertically disposed segment, a platen arranged above the segment, a series of segmentally arranged upwardly and rearwardly striking type bars which are adapted to strike against the front face of the platen and which normally extend substantially horizontally toward the

front of the machine, two sets of parallel shift arms which extend fore and aft of the machine, and on which said segment is carried and by which it is guided in its up and 5 down case shifting movements, said arms turning on fixed centers forward of the type bar segment and the arms of one set extending at a higher elevation than the arms of the other set, type bar actuating links which 10 are operatively connected to the type bars and extend beneath the type bars fore and aft of the machine and which normally are substantially parallel with said parallel shift arms, actuating levers of the first order pivoted on a relatively fixed portion of the machine and pivotally connected to said actuating links, and key levers carried by a relatively fixed portion of the machine and operatively connected to said actuating levers. 15

21. In a typewriting machine, the combination of a substantially vertically disposed segment, a platen arranged above the segment, a series of segmentally arranged upwardly and rearwardly striking type bars 20 which are adapted to strike against the front face of the platen and which normally extend substantially horizontally toward the front of the machine, two sets of parallel shift arms which extend fore and aft of the machine and on which said segment is carried and by which it is guided in its up and 25 down case shifting movements, said arms turning on fixed centers forward of the type bar segment, and the arms of one set extending at a higher elevation than the arms of the other set, type bar actuating links which 30 are operatively connected to the type bars and extend beneath the type bars fore and aft of the machine and which normally are substantially parallel with said parallel shift arms, actuating levers of the first order pivoted on a relatively fixed portion of the machine and pivotally connected to said actuating links, key levers carried by a relatively 35 fixed portion of the machine and operatively connected to said actuating levers, and a cross rod which rigidly connects the parallel shift arms of each set. 40

22. In a front strike typewriting machine, 50 the combination of a type basket containing a system of upwardly and rearwardly striking type bars, a mounting for said type bars comprising parallel arms that turn around different pivotal centers, said mounting being arranged to compel a slight rearward movement off the basket in its case shifting movement from the normal to the shifted position, key levers mounted independently 55 of the type basket and remaining at rest when the type basket is shifted, and intermediate connections between the key levers and type bars, including a series of links which move at one end with the type basket 60 during the case shifting movements thereof the said intermediate connections being ar- 65

ranged to compensate for the said rearward movement of the type basket. 70

23. In a front strike typewriting machine, the combination of a substantially vertically disposed segment, a series of upwardly and 75 rearwardly striking type bars carried by said segment, parallel shift arms arranged at different elevations and turning on fixed centers forward of the type bar segment and arranged to compel a slight rearward movement of the segment in its case shifting movement from the normal to the shifted position and retaining the segment when the latter is in its shifted position parallel to the position of the segment in its normal 80 position, keys mounted against case shifting movement with the segment, and intermediate connections between the said keys and type bars, which connections are so arranged as to compensate for the said rearward 85 movement of the segment and to enable the keys to remain at rest when the type bars are shifted. 90

24. In a front strike typewriting machine, the combination of a substantially vertically 95 disposed segment, a series of upwardly and rearwardly striking type bars carried by said segment and shiftable up and down therewith during the case shifting movement of the segment, parallel motion shift arms of uniform length which turn on a plurality of fixed centers forward of the type bar segment, said shift arms being arranged to compel a slight rearward movement of the segment from one substantially 100 vertical plane to another in the case shifting movement of the segment from the normal to the shifted position, key levers mounted against case shifting movement with the segment, and intermediate connections between said key levers and type bars, said intermediate connections comprising sub-levers arranged beneath the type bars and 105 operatively connected with said key-levers, and links arranged beneath said type bars and operatively connected with said sub-levers and type bars, the said intermediate connections being arranged to compensate 110 for the said rearward movement of the segment and to enable the key levers to remain 115 at rest when the type bars are shifted. 120

25. In a front strike typewriting machine, the combination of a substantially vertically disposed shiftable segment, a system of type bars carried by said segment, parallel motion arms which guide the segment in its case shifting movements and which are arranged to compel a slight rearward movement of the segment when it receives a case shifting movement from the normal to the 125 shifted position, key levers carried by a relatively fixed portion of the machine, and intermediate connections between said key levers and type bars, said connections including a series of links, said intermediate 130

connections being arranged to compel a slight rearward movement of the series of links at one end thereof when the segment is shifted from normal position and to compensate for such rearward movement of the segment and enable the key levers to remain at rest when the segment is shifted.

In testimony whereof I have hereunto set my hand in the presence of two subscribing witnesses.

JOHN W. PAUL.
